Patented Jan. 4, 1927.

UNITED STATES PATENT OFFICE.

ROBERT SUTTER, OF SAINT-IMIER, SWITZERLAND.

DEVICE FOR RETAILING AND MEASURING LIQUIDS.

Application filed March 11, 1926, Serial No. 94,059, and in Germany April 3, 1925.

The present invention relates to a device for retailing and measuring liquids which are drawn off from a supply container into a measuring vessel.

5 The novel feature of the device consists in a hand lever arranged so as to control not only the inlet and the delivery valve and a venting valve of the measuring vessel but also a valve by means of which may be seen 10 in a gauge glass the complete filling of the measuring vessel as well as the remaining level in the container.

The annexed drawing represents as an example one working form of the novel device. Therein are—

Figs. 1 and 3 two side elevations and Fig. 2 a plan view, while

Figures 4, 5 and 6 are diagrammatical views of the device in different positions.

20 With reference to the drawing an open measuring vessel 1 preferably of glass is provided with a delivery orifice controlled by a piston valve 2 opening on the inside of the vessel and is tightly shut by means of a cover 5 a packing ring 4 being kept compressed between said cover and a rim integral with the vessel by means of screws, clamp and a collar 3 of angular cross-section. The discharge neck 7 of a supply container 25 not shown in is bolted to a block 36 which is connected to said cover 5 by means of the flanges 35 and which contains the inlet canal 9 with the inlet piston valve 8 of the measuring vessel. This valve opens upwards and 30 is kept open by a tension spring 10 attached to a sleeve 12 lodged within the cover 11 of the valve box and to a sleeve 13 fast to the valve stem and guided within the first sleeve. Valve 2 however having a valve stem ex- 35

40 tended from the bottom of the vessel to the outside of its cover 5 is kept closed by two springs 16 attached to the cover and to a cross pin 15 stuck through the end 14 of said stem. A hand lever 18 secured to a shaft 19 45 supported in standards 17 is connected near its pivot by means of a link 20 to the one end of a two armed lever 21 which at its other end carries a pin 23 engaged into a fork 22 rigidly fast to the end 14 of valve 50 stem 2. The connection between hand lever 18 and link 20 is effected by a pin 24 fast to said lever and engaged in a slot 25 of said link so that lever 21 will only be moved by said lever and valve 2 be opened when this 55 lever is in its lowest depressed position as shown in Fig. 6. In this position only this

discharge valve 2 will be opened by fork 22. Mounted loosely on shaft 19 is also an arm 27 which is kept in position by a bent finger 28 secured rigidly fast to the lever 18 while a torsional spring 26 sleeved on shaft 19 and fastened at one end to the same tries to swing said arm 27 downwards. In the uplifted position of lever 18 this arm is out of contact with the top end of valve stem 8 but will 60 press this stem downward so as to close said valve 8 only when the lever 18 is depressed into an intermediate position as shown in Fig. 5 and an extreme position as in Fig. 6.

Besides the inlet canal 9 there are also provided in the cover 5 canals 29 and 30. Canal 29 intended as venting means is controlled by a cock and likewise canal 30 which carries an open gauge glass 31 extended to the whole height of the supply tank. The two cocks having their passage ways arranged perpendicularly one to the other are operated by two parallel arms coupled by a link 32 and an arm 33 connects one end of this link to an arm 34 secured rigidly fast to the 70 shaft 19. The relative position of this arm and the arms of the cocks is chosen such, that on the uplifted position of lever 18 (Fig. 4) that is while the inlet valve is open, cock 29 will be closed and cock 30 open. In the intermediate position of lever 18 however, when both valves 8 and 2 are shut and the measuring vessel is filled, said cocks will be closed (Fig. 5) and in the most depressed 75 position of lever 18 (Fig. 6) when the discharge valve 2 is open the venting cock 29 will be open again, while cock 30 remains shut.

The working of this retailing device is as follows:—

For filling the measuring vessel 1 the hand lever 18 is moved from the extreme depressed position as shown in Fig. 6 into the extreme uplifted position as shown in Fig. 4. Thereby the discharge valve 2 will be 100 closed, but the inlet valve 8 will be opened only when the lever 18 has reached its extreme uplifted position. While the filling of vessel goes on the air escapes through the gauge cock 30 and the gauge glass 31 and when the filling is at an end the liquid will rise within the glass up to the remaining level in the supply container. The vessel 1 being filled and lever 18 in its extreme uplifted position the discharge of the liquid is 105 effected by pressing lever 18 down at first into the intermediate position (Fig. 5) where

all valves and cocks are shut and then into the lowest position (Fig. 6) where valve 2 and cock 29 are open.

The position of Fig. 4 is to be considered 5 as the position of rest.

What I claim is:

In a retailing and measuring device for liquids where the liquid is drawn from a supply container into a measuring vessel and 10 in combination a cover secured tightly to the vessel, a connecting neck between the container and cover, a piston valve arranged inside of said neck for controlling the filling of the vessel and having its stem extended 15 to the outside of said neck, a tension spring supporting the piston of said valve in an open uplifted position, a discharge valve in the bottom of the vessel and having its stem

extended to the outside of the cover, tension 20 springs fastened to the end of the valve stem of the discharge valve and to the top side of the cover so as to normally maintain the said valve in closed position, a venting canal and a canal joined to a gauge glass both provided in said cover, cocks arranged so as to 25 control said canals, a shaft mounted in standards on said cover, a hand lever rigidly fast to said shaft and link and lever connections between the shaft and the valves adapted to operate the inlet and outlet valves and to move said cocks so as to secure the mutual perpendicular position of the passage ways 30 of the same.

In testimony whereof I affix my signature.

ROBERT SUTTER.
